US0D1110039S

(12) United States Design Patent (10) Patent No.: US D1,110,039 S
(45) Date of Patent:  Jan. 27, 2026

(54) NONWOVEN FABRIC(71) Applicant: Berry Global, Inc., Evansville, IN (US)(72) Inventors: Vincenzo D'Acchioli, Bergamo (IT);
Sylvie Lesne-Olivier, Lompret (FR)(73) Assignee: MAGNERA CORPORATION,
Charlotte, NC (US)() Term: 15 Years(21) Appl. No.: 29/761,983(22) Filed: Dec. 14, 2020*Related U.S. Application Data

(62) Division of application No. 29/694,635, filed on Jun. 12, 2019, now Pat. No. Des. 907,932.
